CLAIM

The ornamental design for a clock or similar article, as shown and described.

DESCRIPTION

FIG. 1 is a front elevational view of a clock or similar article showing my new design;

FIG. 2 is a top plan view thereof;

FIG. 3 is a rear elevational view thereof;

FIG. 4 is a bottom plan view thereof; and

FIG. 5 is a right side elevational view thereof, the left side being substantially a mirror image thereof.

FIG. 1.

FIG. 2.

FIG. 3.

FIG. 4.

FIG. 5.
